UNITED STATES PATENT OFFICE.

JOHN W. ANDERSON, OF HAMILTON, ONTARIO, CANADA.

REFRIGERATING DEVICE.

Application filed April 14, 1926. Serial No. 102,042.

The principal object of the invention is to simplify the construction and reduce the cost of operation of mechanically operated refrigerating plants.

6 The principal feature of the invention consists in the novel construction and arrangement of the compressor and return from the refrigerating coil, whereby the temperature of the refrigerating fluid in compression is retained at the lowest possible point.

The drawing is an elevational and part sectional view of the complete refrigerating plant.

15 In the construction and arrangement of apparatus as herein shown the compressor 1 for compressing fluid methyl chloride which applicant uses has a piston of the reciprocating type and coiled about the cylinder of the compressor is a copper pipe 2, the upper end of which connects with the intake to the cylinder arranged in the head 3.

The discharge from the cylinder passes through a check valve 4 from whence it is 25 conducted through the pipe 5 to a condensing coil 6 which is arranged within a cylinder 7 through which cooling water is circulated.

30 The coil 6 surrounds a cylinder 8 which forms a retaining reservoir for the methyl chloride.

A pipe 9 leads from the interior of the reservoir preferably from a point close to the bottom thereof to the chamber 10 of the 35 expansion valve 11.

The valve 11 is provided with a diaphragm 12 which supports the valve 13 and said valve is spring held closed by an adjustable spring 14 arranged at the other 40 side of the diaphragm so that a predetermined pressure in the chamber 10 is required to open the valve.

The compressed fluid methyl chloride upon attaining a pressure sufficient to lift the valve from its seat is sprayed into the 45 pipe 15 leading therefrom and immediately gasifies and flows through the coil 16 which is enclosed within a refrigerating casing 17, which is arranged within the "refrigerator" proper, the top 18 only of which is shown as 50 supporting the compressor and the motor 19 for operating same.

A pipe 20 leads from the refrigerating coil 16 and connects directly with the coil 2 surrounding the compressor cylinder. 55

The refrigerating cycle is thus completed. It is extremely simple. The cooling of the compressor cylinder by conducting the discharge from the refrigerating coil around the cylinder, effects a very great economy in 60 operation, as the excessive heat of compression is eliminated, consequently the time element and the necessity for a large volume of water to be used in cooling is dispensed with and the very minimum of cooling water 65 is required.

The parts are extremely simple and can be very readily applied to and supported by the ordinary household refrigerator.

What I claim as my invention is:— 70

In a refrigerating device containing a fluid refrigerating medium, the combination of a compressor; a condenser connected with the compressor; an expansion valve connected with the condenser; a cooling coil connected with the expansion valve; and a tubular coil encircling the compressor cylinder and in heat exchange relation therewith, one end of said coil being in communication with the cooling coil and its other end in 75 communication with the compressor. 80

JOHN W. ANDERSON.
